CLAIM

The ornamental design for the spacer for inhaler, as shown and described.

DESCRIPTION

FIG. 1 is a perspective view of a spacer for inhaler, showing our new design,

FIG. 2 is a front view of the spacer for inhaler of FIG. 1, FIG. 3 is a side view of the spacer for inhaler of FIG. 1, FIG. 4 is a top view of the spacer for inhaler of FIG. 1; and, FIG. 5 is a bottom view of the spacer for inhaler of FIG. 1. The broken lines in the drawings illustrate portions of the spacer for inhaler that form no part of the claimed design.
